US0D1051726S

(12) United States Design Patent (10) Patent No.: US D1,051,726 S
(45) Date of Patent: * Nov. 19, 2024

(54) BOTTLE

(71) Applicant: Diageo North America, Inc., New York, NY (US)

(72) Inventors: William Dohm, Plainfield, IL (US); Amanda Bauman, Plainfield, IL (US); Hania Midura, New York, NY (US); Jeremy Lindley, London (GB); Riley Ruthven, New York, NY (US); Christopher Jenkins, London (GB)

(73) Assignee: Diageo North America, Inc., New York, NY (US)

() Term: 15 Years

(21) Appl. No.: 29/801,334

(22) Filed: Jul. 28, 2021

(51) LOC (14) Cl. 09-01

(52) U.S. Cl.

USPC D9/563

(58) Field of Classification Search

(57) CLAIM

The ornamental design for a bottle as shown and described.

DESCRIPTION

FIG. 1 is a front perspective view of a bottle showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines shown in the drawings are for the purpose of illustrating parts of the article that form no part of the claimed design. All unshaded portions form no part of the claimed design.

1 Claim, 5 Drawing Sheets
